UNITED STATES PATENT OFFICE.

CHARLES H. SIVEL, OF WESTON, NEWARK, ENGLAND.

SAFETY APPARATUS FOR MINING-CAGES, LIFTS, AND THE LIKE.

1,032,710.

Specification of Letters Patent.

Patented July 16, 1912.

Application filed October 28, 1911. Serial No. 657,313.

To all whom it may concern:

Be it known that I, CHARLES HARRY SIVEL, a subject of King George V of Great Britain, residing at Weston, Newark, in the county 5 of Nottingham, England, have invented certain new and useful Improvements in Safety Apparatus for Mining-Cages, Lifts, and the Like; and I do hereby declare the following to be a full, clear, and exact description of 10 the invention, such as will enable others skilled in the art to which it appertains to make and use the same.

This invention relates to safety apparatus for mining cages, lifts and the like, and has 15 for its object to provide an improved form of such apparatus of simple and efficient construction.

The invention comprises a spring pressed shoe or member pivotally mounted upon the 20 cage, adapted normally to be held from engagement with a frictional surface on the wall of the shaft by a catch device, which catch device is adapted to be engaged to release the shoe when the hauling cable breaks, 25 by means of a member normally held inoperative by the tension of the cable. The spring which bears against the shoe to create the necessary friction is obviously of a powerful nature and for the purpose of re- 30 turning the shoe to the off position after it has been in use, I provide a screwed member, adapted to be detachably secured to the shoe and provided with a nut or the like which may be operated by a person within the cage 35 to allow of the catch device being placed in position whereupon the said screwed member may be detached and removed.

The accompanying drawings illustrate the 40 invention applied to a mine cage.

Figure 1 is a sectional elevation of a cage with the invention in the out of use position. Fig. 2 is a part similar view with the parts in use; also the retracting device in position. Fig. 3 is a detail.

In the drawing the mine shaft *a* is provided with friction surfaces in the form of channel bars *b* extending the full length of the shaft disposed on opposite sides thereof.

A similar safety device is provided at each 50 side of the cage. A shoe or friction member *c* is provided at its upper end with an arm *c'* which is arranged at an angle to the shoe, and the upper end of this arm is pivoted to a bracket on the side of the cage by means of 55 a pin *d*. The shoe is pressed outward from the cage by a powerful laminated spring *e*.

f is a bar pivoted to the shoe at *f'* and projecting into the cage through the opening *f''* therein. The bar *f* is provided with a nose or catch *g* adapted normally to be kept in 60 engagement with a plate *h* by means of a spring *i* and the end of the arm is provided with a slotted hole *j* (Fig. 3).

k is a cord connected at its upper end to the suspending ring *l* and secured at its 65 lower end to a spiral spring *m* said cord passing through the slotted end of the bar *f* and provided with a block or enlargement *n* disposed just above the said slot.

It will be seen that with the parts in the 70 position shown in Fig. 1 the safety device is out of use and upon the hauling cable breaking or the tension thereof being reduced the spring *m* will at once draw down the cord *k* the block *n* strikes the bar *f* and releases the 75 nose *g* from engagement with the plate *h* and thus allows the shoe to be pressed tightly against the frictional surface by the spring *e* and thus the descent of the cage will be stopped or checked so as not to endanger the lives of the occupants. After 80 the apparatus has been in use as above described and the fault in the hauling mechanism or cable repaired, it is necessary to retract the shoe from engagement with the 85 frictional surface and to effect this end I provide a screwed rod *p* having a loop at one end which may be inserted through a bush *q* in the cage and placed over a hook *r* on the shoe. The rod *p* is provided with a 90 threaded nut *s* having a suitable operating handle or hand wheel *t* which nut when the hand wheel is turned fits in and bears against the bush *q* and draws in the rod, and with it the shoe. The pivoted catch 95 arm *f* returns to the position shown in Fig. 1 whereupon the nut *s* is unscrewed, the rod *p* disengaged from the hook on the shoe and placed in some convenient place until again required.

Having now particularly described my 100 said invention what I claim as new and desire to secure by Letters Patent is:—

1. The combination, with an elevator cage, a lifting device therefor, and a stationary safety-bar; of a shoe pivotally connected with the cage at one end and adapted to engage with the said bar, a spring for pressing the shoe against the said bar, a rod connected to the said shoe at one end and 105 projecting into the cage and provided with a catch at its free end portion, a stop on the 110

cage which normally engages with the said catch, and spring-actuated tappet-mechanism carried by the said cage and connected with its lifting device, and operating to release the said catch when the cage is not supported by its lifting device.

2. The combination, with an elevator cage, a lifting device therefor, and a stationary safety-bar; of a shoe provided with an arm at one end which is pivoted to the cage, a leaf spring secured to the cage and operating to press the shoe against the safety-bar, a rod connected to the shoe at one end and projecting into the cage and provided with a catch at its free end portion, a stop on the cage which normally engages with the said catch, and spring-actuated tappet-mechanism carried by the said cage and connected with its lifting device, and operating to release the said catch when the cage is not supported by its lifting device.

3. The combination, with an elevator cage, a lifting device therefor, and a stationary safety-bar; of a shoe pivotally connected with the cage at one end and adapted to engage with the said bar, a spring for pressing the shoe against the said bar, a rod connected to the said shoe at one end and projecting into the cage and provided with a catch at its free end portion, a stop on the

cage which normally engages with the said catch, a flexible connection having its upper end secured to the lifting device of the cage, a spring arranged between the lower end of the flexible connection and the cage and 35 normally holding the said connection taut, and a tappet secured to the flexible connection and arranged above the free end portion of the said rod and operating to release it from the said stop when the cage is not 40 supported by its lifting device.

4. The combination, with an elevator cage, a lifting device therefor, a stationary safety-bar, and a spring-pressed shoe pivoted to the cage and engaging with the said 45 safety-bar; of a catch secured to the said shoe, a bush secured to the cage, a screw-threaded rod slidable in the said bush and detachably connected to the said catch, and a retracting device screwed on the said rod 50 inside the cage and bearing against the said bush and adapted to move the shoe out of engagement with the safety-bar.

In testimony whereof I affix my signature, in presence of two witnesses.

CHARLES H. SIVEL.
